(57) **CLAIM**

The ornamental design for a door component extrusion assembly, as shown and described.

DESCRIPTION

FIG. 1 is a front isometric view of a door component extrusion assembly showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines are for the purpose of indicating break lines and portions of the door component extrusion assembly that form no part of the claimed design.

In FIGS. 1-5, the door component extrusion assembly is shown with a symbolic break in its length. The appearance of any portion of the door component extrusion assembly between the break lines shown forms no part of the claimed design.

1 Claim, 7 Drawing Sheets
